DROP SHEET ELECTRIC CURRENT
OPERATED INTERLEAVER

James E. Jolley, Santa Rosa, Calif.

Application November 24, 1952, Serial No. 322,298

2 Claims. (Cl. 101—419)

1

My present invention relates to interleavers and more particularly to slip sheet interleavers operated by electrical impulse.

The principal object of my invention is to produce an improved slip sheet interleaver.

Another object is to produce an improved interleaver which is actuated by electrical impulse for use with duplicating machines.

Other objects and novel features comprising the construction and operation of my invention will be more apparent as the description of the same progresses.

In the drawings illustrating the preferred embodiment of the apparatus:

Fig. 1 is a side elevation of the interleaver coupled to a duplicator, the duplicator being fragmentarily shown in dot-and-dash lines;

Fig. 2 is a fragmentary cross-section taken on the lines 2—2 of Fig. 1, portions of which are shown in dot-and-dash lines and other portions of which are shown in elevation;

Fig. 3 is a cross-section taken on the line 3—3 of Fig. 2, and

Fig. 4 is a cross-section taken on line 4—4 of Fig. 2.

Fig. 5 is a diagrammatical showing of the various parts together with a wiring circuit.

Referring more in detail to the drawings, 10 indicates any type of duplicator with which a slip sheet interleaver might be used.

The interleaver concerned with the present application comprises a base 11 mounted up against the delivery side of the duplicator, in any suitable manner. On the base 11 are mounted at either side supporting members 12 secured to the base 11 by bolts 13 threaded into a top header base 14. Centrally located in the top header base 14 is a boss 15 in which is secured by set-screw 16 a post member 17 which is of circular outside shape. The lower portion of the post 17 is slotted all the way through from side to side, as indicated at 18. From the top of the slot 18 to the outer top end of the post 17 there is a narrow central slot 19 which extends part way from side to side but terminates at the solid portion 20. In this narrow slot 18 is pivoted at 21 an alternating lever 22. The bottom end of the lever 22 is provided with a pin 23 which extends outwardly from each side of the lever 22. On each side of the lever 22 and pivoted on the pin 23 are a pair of dog members 24 and 25. On the far and near side, the near side being cut away, in the slot 18, are pins 26. The lever 22 oscillates between the pins 26 riding across the faces of them but the upper

portions of the dogs 24 and 25 slide in contact under the bottom surface of the pins 26.

On the post 17 are loosely mounted the interleaves 27. The interleaves 27 are provided with alternate side slotted openings such that when the lever 22 is in the position shown in Fig. 2 the dog 24 is up against solid material and holds the pack of leaves up. When the lever 22 is pivoted in a reverse direction, the dog 25 passes through the slot of the under sheet and engages the next or second sheet from the bottom permitting the bottommost sheet to drop. This type of interleaver sheet release is well known in the art and is in common use. My present invention is concerned with the means of operating this drop sheet mechanism. Hereafter, in the specification and in the claims this mechanism will be referred to as a unit by the term alternating drop sheet mechanism.

In interleaver devices, speed is of great importance and in devices which are wholly dependent on mechanical apparatus there is a delay due to links, leavers and the like which slow down operation.

25 In my present device the operation of the alternating drop sheet mechanism operates instantaneously with the rotating drum of the duplicator. This is accomplished by electrical impulse from a timing cam 30 on the duplicator in which one revolution of the cam 30 represents one complete cycle of the duplicator. The cam 30 operates any simple microswitch 31 which energizes the interleaver mechanism through any electrical current supply source such as 32. Switch 33 may be located on the interleaver apparatus so that the duplicator can operate without operating the interleaver when so desired.

30 On the top header base 14 of the interleaver, are located two oppositely opposed solenoids 40 and 41, the armature portions 42 and 43 of which are connected together and to which is pivoted at 44 the upper end of the lever 22. The solenoids 40 and 41 are energized alternately by any electrical means, as 32.

35 Mounted on the top header base 14 is a relay comprising a solenoid 50 which actuates the armature 51, to the front end of which is pivoted a dog member 52, slidably operated through a guide portion 53, and engages the toothed wheel 54 located on the shaft 55. Also fixed to the shaft 55 is a special gear wheel 56 having alternating high and low notches 57 and 58 respectively. Also mounted on the header base 14 is a set of telephone jacks the common lever of

which is indicated at 60 having a looped end which engages in the high and low notches of the gear 56. When the looped end of the jack lever 60 engages in the low notch 58 the lever 60 contacts with the lower lever 70, and when the lever 60 engages with the high notch 57 the lever 60 contacts with the lever 80. Each time the solenoid 50 is energized one of the solenoids 40 or 41 is energized but always in an alternate manner. This action causes the lever 22 to be thrust from one side to the other alternately engaging the dogs 24 and 25 with the sheets 27 permitting the lower one to drop. This action takes place on each revolution of the cam 30 which corresponds to each rotation of the duplicator drum or one duplicating cycle.

I wish to point out that the action is of an electrical impulse nature and the electrical current is momentary. It is not necessary for the solenoids 40 and 41 to be energized continuously but only long enough for the lever to be thrown from one side to the other. The leverage action between the lever 22 and pivot 23 is such that the dogs 24 and 25 are locked when in the position of dog 24, or in the up position.

The momentary action of the energizing of the solenoids 40 and 41 eliminates all hum or chattering in the solenoids 40 and 41 as is sometimes present where the electrical current is of a sustained nature. The solenoids 40 and 41 are mounted on rubber cushions 90 on the header base 14, all of which make the operation of interleaver very silent.

While I have shown and described my invention somewhat in detail yet it is to be understood that I may vary the shape and proportions within wide latitude without departing from the spirit of the appended claims.

Having thus described my invention what I claim as new is:

1. A drop sheet electric current operated interleaver for electric operated duplicating machines comprising, a base, a header mounted on said base, alternating drop sheet mechanism hung from said header and having an alternating slip sheet actuating lever pivoted in said header, oppositely opposed solenoids mounted on said header on either side of the upper end of said actuating lever, a cam connected to said duplicator connected with and actuating a microswitch, an electro-magnet controlled by an electric switch actuated by said cam, an armature operated by said electro-magnet, means connected to said armature for opening and closing an electric switch alternately opening and closing an electric circuit to said solenoids.

2. A drop sheet electric current operated interleaver as set forth in claim 1 in which said means for operating said solenoids comprise ratchet wheel operated by pusher lever pivoted on said solenoid, and electric two-way switch having a central throw contact lever connected with one side of an electric circuit and having an extension lever engaging with a notched wheel fixed to said ratchet wheel, said notches being alternately high and low for the purpose of alternately engaging said central throw contact lever to the right and left on alternately opposite sides of said two-way switch, said solenoids being alternately energized by said two-way switch.
